Dec 11/48

John Martino & James Norton, of Philadelphia, Pa.
Assignors to
D. Stuart & J. R. Peterson, of same place.
Letters Patent No 1148, Dated Sept 20, 1859.

The schedule referred to in these Letters Patent and making part of the same.

To all whom it may concern:

Be it known that We, John Martino & James Norton, of the City and County of Philadelphia, and State of Pennsylvania, have invented or produced a new and original design for the plates of a cylinder Stove, and We do hereby declare the following to be a full clear and exact description of the same, reference being had to the accompanying drawing and to the letters of reference marked thereon.

Our design relates to the ornamental figures and forms on the plates of a cylinder Stove which we term the "Sun-beam".

On reference to the accompanying drawing, which forms a part of this Specification.

Fig: 1. is a front view of the Stove, the sheet iron cylinder being represented by dotted lines.

Fig: 2. one of the side plates of the base.

Fig: 3. a view of the top plate.

Fig: 4. a view of the upper plate of the base.

Fig: 5. a view of the bottom plate, and

Fig: 6. a sectional view, full size, of the moulding on the edge of the bottom plate.

The top, plate A, the edge view of which is seen in Fig: 1. and the plan in Fig: 3. is edged with a overhanging moulding pierced with ornamental openings a, with a spring between each opening and within this moulding is another having foliated springs, inclosing a third moulding with foliated scroll work.

Each of the side plates which are represented by Fig: 2. has at each end a vertical moulding with lozenge shape projections and is edged on the top and bottom by a plain bead, the panel thus enclosed being furnished with a scroll foliated ornament.

Des. 1148

The upper plate of the base represented by Fig: 4. is edged with a plain moulding and has four projections b. b. having foliated ornaments as well as a foliated ornament on each side of the opening c. in front of the plate, which has also a denticated heading e. within the outer moulding.

The form of the bottom plate and its ornamental mouldings and figures is represented in Fig: 1 and 5, the full sized section of its outer moulding being represented in Fig: 6.

We claim the combination and arrangement of the ornamental figures and forms represented in and by the accompanying drawing as forming together the plates of a cylinder stove.

In testimony whereof we have signed our names to this specification in the presence of two subscribing witnesses.

Witnesses.
